UNITED STATES PATENT OFFICE.

EMIL JAGENBERG, OF DUSSELDORF, GERMANY.

WRAPPING-MACHINE.

1,140,039.

Specification of Letters Patent. Patented May 18, 1915.

Application filed March 10, 1914. Serial No. 823,672.

To all whom it may concern:

Be it known that I, EMIL JAGENBERG, a subject of the German Emperor, and resident of 107 Himmelgeisterstrasse, Dusseldorf, Germany, manufacturer, have invented certain new and useful Improvements in and Relating to Wrapping-Machines, of which the following is a statement.

The present invention relates to a wrapping device for wrapping machines, which serves for partly wrapping and simultaneously sharply folding the wrapping sheets for rectangular packages, boxes, vessels and the like.

The subject of the present invention is exemplified in the accompanying drawing.

Figure 1 is a side elevation, Fig. 2 is a part section on the line A—B in Fig. 1, Fig. 3 is a cross section through the wrapping device on an enlarged scale. Figs. 4 to 6 show packages with the wrapping sheets at different stages of the operation.

The package 1 is fed on the endless belt conveyor 2, which is driven by means of a pawl feed gear 3 intermittently from a cam on shaft 4. The first package is taken from this belt 2 by means of grippers 5 and moved into the wrapping position. The arms 6 of the grippers 5 are pivotally fitted to the slides 7, which are reciprocated by aid of levers 8 from a cam on the shaft 4, and are slidably fitted in sleeves 9, which are hinged to levers 10. These levers are fitted to vertical shafts 11 which are rocked by cams fitted to shaft 4. When the levers are rocked inwardly, the grippers close, and vice versa. When the packet has been advanced by the grippers, the web of paper 25, which unwinds from the roll 26 is drawn forward by means of tongs 22, which are fitted to a slide 23, reciprocated by means of a lever 24 from a cam fitted on shaft 4. The roller 27 applies adhesive to the respective parts of said paper. The web of paper 25 thus lies beneath the package. Now two rods 13 slidably fitted in the body of the machine are lifted by means of bell crank 12. To these rods 13 are secured two plates 14. The lever 12 carries a roller 15 which engages in a cam disk 17 fitted to shaft 16. At the same time a plate 18 is lowered from above onto the package, the said plate being fitted to a rod 19 slidably fitted in the body of the machine, which is operated by means of a lever 20, a rod 21 and a cam 70. The package is thus, at top and bottom inclosed

between the plates, which now are simultaneously lowered, and thereby force the package between the folding walls 28, 28^a. While the package is thus forced down, the knives 29 will have cut off the wrapping sheet of the required length, by the lower knife, which is fitted to a rod 30 being forced upward by a cam 31, and the tongs 22 have opened in consequence of a small advance of the slide 23 to the left, (Fig. 1), as the upper arms of the tongs have been lifted by means of a rod 32 moving in a clamp. The ends of the wrapping sheet are thus free and are now turned upward by the walls 28, 28^a (Fig. 4). To the folding walls are fitted bolts 33, 33^a, which are displaceably fitted in brackets 34. The bolts 33^a can be fixed in position by means of screws 35, and the bolts 33 are forced forward by springs, 75 but may be withdrawn by a crank 36. The wall 28^a is so adjusted, that the package fits tightly between the folding walls. The wrapping sheet is thus smoothed down at the sides. Then the folding slides 37, 37^a 80 are successively advanced, which are hinged to levers 38, operated by aid of rods 39 from cams on shaft 40. The inner ends of the slides thereby glide over the upper edges of the folding walls. The folding slide 37^a 85 does, however, not recede, but remains in its advanced position, so that it holds down the wrapping sheet which has been folded over (Fig. 5).

At both sides of the plate 18 the wrapping slides are arranged. These consist of plates 42 hinged to slidable rods 41, the said plates being slightly curved at top and bottom and provided with likewise curved flat springs 43. To these plates 42, and at right angles 95 to their face, narrower plates 45 are fitted on bolts 44 which plates 45 are likewise curved at top and bottom and fitted on their inner side with curved flat springs 46. Against the flat springs bear rollers 47 and 100 48, which are fitted to arms 49 and 50, respectively, which again are fitted to rods 51, arranged next to rods 41. The rods 41 and 51 are fitted into the same guides in the body of the machine, but are displaceable 105 relatively to each other, as the upper ends of the rods 51 are loosely fitted in slots 52, formed by the plates 53 fitted to rods 41. The rods 51 are held in their lifted position by means of bolts 54 fitted to them and levers 110 55, fitted to shaft 56, which is turned by a lever 57, a rod 58 and a cam on shaft 4.

By their gravity the plates 42 and 45 weight downward, so that their rods bear with the plates 53 on the rods 51. When these rods 51 are lowered by the turning of levers 55, 57 therefore also the folding plates 42, 45 move down and press the parts of the tubular wrapped paper projecting at the sides beyond the package down on the top surface (Figs. 3, 6). The folding walls are 10 of the same length as the tubular wrapping, so that the plates 45 slide down along their inner sides. The result is that the paper wrapping is smoothly folded down. When, now, the plates 42, 45 bear down on the 15 plates 53, or when the plates 53, which have shoulders 59, bear against elastically fitted bolts 60, the rods 51 will be thereupon further lowered alone, and the rollers 47, 48 fitted to them will glide downward on the 20 flat springs 45, 46 and rock toward outside in consequence of the curved shape of the plates 42, 45, so that they are pressed against the package or the folding walls respectively. Thereby the wrapping sheet will be 25 folded over sharply (Fig. 6). When the rods 52 move upward again, the rollers 47, 48 glide off the flat springs, so that the springs 61 can withdraw the folding plates, and then the upper ends of the rods 51 bear 30 against the plates 53, so that also the rods 41 are lifted.

After the wrapping has been folded on the upper side, the package is pushed by means of a slide 62 longitudinally from 35 the space between the folding plates. The slide 62 is fitted to a carriage 63, which is reciprocated by means of two levers 64, 65 coupled together, of which levers the lever 65 engages with a roller in a cam disk 66. 40 The carriage 65 has a bevel 67 and on it rests the free arm of the bell crank 36, by means of which the folding wall 28 is withdrawn. When the carriage 63 is displaced, the bevel 67 forces the free arm of the bell 45 crank 36 upward, and the folding wall 28 recedes, and by means of a lever 68, which is coupled by means of rod 71 with a lever 69, the folding slide 37^a is lifted. The package 50 is thus lying loose between the folding walls and may be easily removed by the slide 62.

The package is then pushed to a wrapping device which completely closes the wrapping.

I claim;

1. In a wrapping machine, a plate adapted to engage the wrapper at the end of a package, a pair of additional plates extending outwardly at right angles thereto and adapted to double portions of the wrapper protruding from said end, means for forcing the first named plate against the package, and additional means for forcing the last named plates against said doubled wrapper-portions.

2. In a wrapping machine, a resilient folding plate, a pair of additional resilient folding plates extending outwardly at right angles thereto, a roller engaging the first named plate, a pair of rollers engaging the last named plates, means for sliding the plates along a package and means for advancing the rollers against the plates.

3. In a wrapping machine, a resilient folding plate, a pair of additional folding plates extending at right angles thereto, 75 slideable rods carrying all of said plates, rollers engaging the plates, second slideable rods carrying the rollers, and apertured members on the first named rods that engage the last named rods.

4. In a wrapping machine, a pair of folding walls adapted to engage the sides of a package, one of said walls being movable, a carriage, a slide fitted to the carriage and adapted to push the package from out between the walls, and means actuated by the carriage for retracting the movable wall.

5. In a wrapping machine, a pair of folding walls adapted to engage the sides of a package, one of said walls being movable, 90 a pair of hinged folding plates adapted to engage the top of said package, a carriage, a slide connected to the carriage, means on the carriage for retracting the movable folding wall, and means for lifting one of the folding plates.
